US0D1044980S

(12) **United States Design Patent** (10) **Patent No.:** **US D1,044,980 S**
(45) **Date of Patent:** **** Oct. 1, 2024**

(54) **GRIP FOR EXERCISE EQUIPMENT**

(71) Applicant: **Hyun Woo Kim**, Seoul (KR)

(72) Inventor: **Hyun Woo Kim**, Seoul (KR)

(**) Term: **15 Years**

(21) Appl. No.: **29/811,270**

(22) Filed: **Oct. 13, 2021**

(30) **Foreign Application Priority Data**

Apr. 26, 2021 (KR) 30-2021-0020165

(51) **LOC (14) Cl.** **21-02**

(52) **U.S. Cl.**

USPC **D21/684**; D21/662; D21/694

(58) **Field of Classification Search**

USPC D21/694, 684, 662, 797; 482/139, 106, 482/93; 2/170, 161.1, 20; D29/113, D29/117.1, 117.2

CPC . A63B 21/4021; A63B 71/14; A63B 2209/10; A63B 21/4001; A63B 21/4019; A63B 21/065; A41D 19/01547; A41D 13/0568; A41D 13/081; A41D 2400/80; A61B 5/224; A61B 17/1322

See application file for complete search history.

Primary Examiner — Ryan Harvey

(74) *Attorney, Agent, or Firm* — Sughrue Mion, PLLC

(57) **CLAIM**

The ornamental design for a grip for exercise equipment, as shown and described.

DESCRIPTION

FIG. 1 is a perspective view of a grip for exercise equipment showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 6 Drawing Sheets
